UNITED STATES PATENT OFFICE.

WALTER BENNEY, OF NEW YORK, N. Y.

FIRE-ESCAPE.

SPECIFICATION forming part of Letters Patent No. 737,197, dated August 25, 1903.

Application filed July 3, 1903. Serial No. 164,149. (No model.)

To all whom it may concern:

Be it known that I, WALTER BENNEY, a citizen of the United States of America, residing at New York city, in the county and State of New York, have invented certain new and useful Improvements in Fire-Escapes, of which the following is a specification, reference being had to the accompanying drawings, forming part of the same, in which—

10 Figure 1 is a front elevation of a device embodying my invention in position for use in descending from a building in which there is a fire. Fig. 2 is a side elevation of such device in the position it may occupy when not in use. Figs. 3, 4, 5, and 6 are detail views of the steps of the escape, showing various modifications. Figs. 7 and 8 are front and side elevations of a balcony or platform in position for use. Fig. 9 is a front view of the same 20 when lowered out of the way. Fig. 10 is a sectional view of the same when lowered, and Fig. 11 is a detail view of part of the platform-operating mechanism.

The object of the invention is to provide 25 ready means of exit from a building in case of fire in such form that not only athletes, but also every one capable of walking down a stairway, may avail themselves of the escape and at the same time to so arrange said means 30 that when not required it may be folded back out of the way; and it consists in a series of steps arranged to be swung into a spiral stairway or back out of the way and means for operating the series from any desired floor.

35 In the drawings, H is supposed to be the wall of a house, and my fire-escape is applied thereto.

P is an upright post which is supported in any suitable manner, here by braces B, secured to and extending from the wall of the 40 house.

S represents the steps of the escape, and they consist of a tread or platform T and a sleeve s s', usually and preferably constructed 45 as two rings surrounding post P, held in their respective vertical adjustment by collars C, secured to the post. It is of course manifest that the steps might be held in place by having the bottom of one sleeve rest upon 50 the top of the next lower sleeve; but I prefer to support them independently. I also prefer to construct the sleeve in two parts, se-

cured together by bolts b, as shown plainly in Fig. 3, that one may be removed, if necessary, without disturbing the others; but this, too, 55 is not a necessity. These steps are intended to be arranged in the form of a spiral staircase when in use, as shown in Fig. 1, but to stand vertically under each other at other times, and they must therefore be capable of oscillatory 60 movement upon the post or support. Means must also be provided for oscillating them quickly and easily, and as one link in mechanism for that purpose I prefer to provide each with an aperture a, extending nearly across the 65 width of the step, and a lug l, extending from each step to a point beyond the level of the next in one direction, so placed that it may enter the aperture a of said next step and bear against one or the other of the side walls 70 thereof, which thereby become steps, as shown. The result will be that if one step is oscillated from one position—say that of Fig. 2—then as soon as its movement has progressed sufficiently to clear its tread from a 75 vertical registry with the succeeding step, and to thus constitute the two parts of a flight of steps naturally placed, this lug will engage the rear side of the wall of aperture a and thereafter the two steps will move together, 80 and such action taking place successively from the first to the second step and then the second to the third, and so on, the continued movement of the first step will result in all of any given series being swung from their 85 positions of vertical registry to their positions in a complete series of naturally-placed steps in a complete spiral stairway, as shown in Fig. 1. Correspondingly when it is desired to close them up, the first step being swung 90 back, its lug will engage the front wall of the aperture a and thereafter carry along the second step, and then, through its agency, the third, and thus the entire series may be operated from one point.

In lieu of the aperture a and lug l I may employ a jointed link j, as shown in Fig. 4, with a throw equal to the movement required to bring the steps in proper registry from their position as a series of stairs to their positions in vertical registry, locating the respective pivots at such relative points that in one position one will be as far on one side of a vertical line from the other as in the other 95 100

position it will be on the opposite side of such line, thereby insuring accurate location of the respective steps in their respective positions. I also prefer to provide a standard or balustrade-post p for each step and a chain-rail c , running from one post p to the next, the posts being provided with an offset, as shown, that the steps may return to accurate vertical registry when closed, and I find that these posts p and chain c may be utilized to swing the succeeding steps into one and the other desired positions, if preferred.

When the stairway is being opened, the chain, then slack, will first straighten from one post to the next and thereafter pull after it the succeeding step, as would the jointed link, and when the stairway is being closed one step having moved to a position vertically over the next will be stopped by the post p of said next step and thereafter the two steps, and successively one, two, three, &c., will move together to the closed position. If no chain is used, I may employ an offset-post p' , as shown in Figs. 5 and 6, to perform this function of the chain. Said post p' reaches from one step to a point where it will be engaged by a flange or stop f' on the next, the location of the stop and the offset of post p' , one or both, being so calculated that each step will have the requisite independent oscillation to give it the proper position in the series of stairs by the time said post p' engages said stop f' .

To operate the first step of a series, and thus move the series, I have shown a pair of gear-wheels—one a vertical gear G , mounted on a shaft A , (supported in bearings on the post P and the house,) and a horizontal gear G' , meshing with gear G , mounted on said post P and secured to rotate with the said first step of the series, a crank L on shaft A being provided within the house or at some other suitable and convenient location. The gear G' might readily be arranged with its toothed side down.

I prefer to provide a shaft and crank on each floor of the building and to operate the steps of the flight from only one floor to the next, from any given gear, to insure ease of operation, and to permit this and yet allow the entire escape to be operated from each point I use a shaft A and crank L at one floor, a shaft A' and crank L' at the next floor, and a shaft A^2 and crank L^2 at the bottom, and as many more as may be desired. Then on each shaft I secure sprocket-wheels W W' W^2 , and from one to the next I carry sprocket-chains C C' , &c., whereby the entire system is connected and may be operated from either location. Indeed, from other locations, too, as by seizing the chain at any point and exerting force in the proper direction, the axles will be caused to turn and the stairway to open or close.

To provide ready means for getting from a window or door upon the steps of the stairway, I provide balconies or platforms, and as

permanently horizontal ones are likely to be obstructed by occupants of the building I have constructed mine to close downward when not in use and to be opened and secured in horizontal position by suitable connection with the means for operating the stairway.

Hinged in suitable brackets B' is a shaft D , to which the floor F of the balcony is secured, the whole preferably so located that when turned down its upper edges will be covered and protected by the window-sill w or other suitable protector. On this platform F is a guard-rail r and a supporting-link r' , hinged to said rail and to the building. Beneath, the platform has supports, preferably two, in the form of legs f , with notches n at the lower ends. The shaft D carries near each end a gear G^2 , and in brackets B' are vertical shafts D' , each provided with a gear G^3 , meshing respectively with gears G^2 of shaft D . From shafts D' , I extend wing-supports or braces b' and on chain C' , I provide a lug l' , so placed as to engage with the platform F at a point on one side (here the front) of the pivoting-shaft D . A counter-balance-weight m may be secured to platform F by a chain c' , extending around and to the rear of shaft D , and the lifting of the platform thereby rendered easier, if desired. Now when the chain C' is moved to open the stairway the lug l' will approach and taking under the edge of platform F will swing it outward and upward, thus oscillating shaft D , which acting through gears G^2 G^3 will turn outward the wing-supports b' , the weight m assisting in that operation. The wing-supports will come to engagement with legs f and rest in the notches in their feet, the rail r and link r' being at the same time carried to the position shown in Fig. 8, and a complete and safe balcony is provided to permit ready escape from the window or door at which it is located and convenient access to the stairway then in position for use. When the stairway is closed, the wings may be swung in. The lug l' will then have moved from its engagement with the platform, and that may be readily returned to its hanging position.

I have thus a fire-escape which may be closed into small compass and into a position of the relative parts which avoids the unsightly character of many of such devices and insures that it shall not be encumbered with articles which would obstruct its use in time of need, and yet by a simple and easy operation it may when needed be opened into a complete, safe, and easy stairway down which the most timid may easily proceed and to which easy access may be had.

I do not limit myself to the exact details of construction shown. It might be operated without the shafts A , gears G G' , and cranks L . A windlass and rope might be substituted for those devices. In fact, one standing on the ground might seize the lower step and force it around, thus operating the others, and many other variations from my exact construction

might be utilized, and yet all be within the spirit of the invention disclosed.

What I claim, and desire to secure by Letters Patent, is—

5 1. The combination with a building, of a fire-escape composed of a rigid support, a series of steps secured thereon in different horizontal planes free to turn in their respective planes and reaching from one place of exit in said building to the level of a lower opening in said building, together with means for operating said steps, substantially as set forth, whereby they may be made to constitute a spiral stairway escape or a vertically-placed series of step-treads, all substantially as set forth.

2. The combination with a building, of a fire-escape composed of a rigid support, a series of steps secured thereon in different horizontal planes, free to turn in their respective planes and reaching from one place of exit in said building to the level of a lower opening in said building, each step being provided with an aperture adapted to receive a lug on the preceding step and a lug adapted to enter the aperture on the succeeding step, together with means for operating said steps, substantially as set forth, whereby they may be made to constitute a spiral stairway escape or a vertically-placed series of step-treads, all substantially as set forth.

3. A swinging balcony composed of a hinged platform, a swinging support therefor, means substantially as described for forcing said platform into horizontal position and carrying said support under and into engagement with said platform, thus placed, substantially as set forth.

4. A rigid support carrying a step secured in permanent horizontal position thereon, but free to oscillate in a horizontal plane, gears adapted to oscillate said step, a chain for operating said gears, a swinging balcony composed of a swinging platform, a swinging support therefor, gears connecting said platform and said support and an engaging device on said chain adapted to engage said platform, all arranged substantially as set forth, whereby when said chain is operated to oscillate said step, said lug will engage said platform and raise it and at the same time swing the support into engagement therewith, all substantially as set forth.

5. In a fire-escape, a post rigidly supported proximately to a building, a series of hori-

zontal steps sleeved thereon, but free to oscillate, engaging devices limiting the independent and causing a coincident movement of one step with the next, a shaft provided with a crank and a gear, a second gear secured to 60 a step and meshing with the gear on said shaft, a chain passing around said shaft and extending to a distant and convenient location, a swinging platform adjacent to said chain, a swinging support thereunder, a gear 65 secured to the shaft of the platform, a gear meshing therewith secured to the shaft of the swinging support, and a lug on said chain, all substantially as set forth, whereby the movement of said chain will cause said step 70 to be swung into position to form a stairway and said platform to be raised and supported in proximity to said stairway, all substantially as set forth.

6. The combination with a building, of a 75 fire-escape composed of a rigid support, a series of steps secured thereon in different horizontal planes, free to turn in their respective planes and reaching from one place of exit in said building to the level of a lower opening 80 in said building, one step being provided with a stop and the next with an engaging device whereby proper relative movement and position will be secured, together with means for operating said steps, substantially as set 85 forth, whereby they may be made to constitute a spiral stairway escape or a vertically-placed series of step-treads, all substantially as set forth.

7. The combination with a building, of a 90 fire-escape composed of a rigid support, a series of steps secured thereon in different horizontal planes, free to turn in their respective planes and reaching from one place of exit in said building to the level of a lower opening 95 in said building, together with means for operating said steps from said different levels, substantially as set forth, whereby they may be made to constitute a spiral stairway escape or a vertically-placed series of step-treads, all substantially as set forth.

In testimony whereof I have signed my name to this specification, in the presence of two subscribing witnesses, this 31st day of March, 1902.

WALTER BENNEY.
